William T. Saunders, Weirton, W. Va., assignor to
National Steel Corporation, a corporation of
Delaware

Filed July 7, 1966, Ser. No. 3,900

Term of patent 14 years

(Cl. D58—26)

FIG. 1

FIG. 2

FIG. 3

FIG. 4

FIG. 5

FIG. 6

FIG. 7

FIG. 1 is a top plan view of an end closure for a container showing my new design;

FIG. 2 is a sectional view taken along the line 2—2 of FIG. 1;

FIG. 3 is a sectional view taken along the line 3—3 of FIG. 1;

FIG. 4 is a top plan view of an end closure for a container showing my new design, wherein the reinforcing rib is reversed and wherein a depression of the configuration shown is formed in the closure;

FIG. 5 is a sectional view taken along the line 5—5 of FIG. 4;

FIG. 6 is a top plan view of an end closure for a container showing my new design wherein another configuration for the depression in the closure is shown;

FIG. 7 is a sectional view taken along the line 7—7 of FIG. 6.

The broken line showings of pull tabs in FIGS. 5 and 7 are for illustrative purposes.

This application is a continuation-in-part of my earlier application Ser. No. D.85,742, filed June 15, 1965, and now abandoned.

I claim:

The ornamental design for an end closure for a container, as shown and described.
